SLIDE FASTENER

Isidore Goldstein, New York, N. Y.

Application November 10, 1943, Serial No. 509,650

2 Claims. (Cl. 24—207)

1

This invention relates to new and useful improvements in a slide fastener.

More specifically, the invention proposes the construction of a slide fastener in the form of a closure for an article having an opening with flexible beads extending along the edges thereof and a series of clips slidably mounted on said beads for location at different distances from one end of the article in a manner to close the open side thereof.

A further object of the invention provides the provision of strategically located small projections along the length of the beads in a manner to stop the clips at even spaced positions along the length of the beads in a manner to eliminate the use of the cord generally applied to clips of this type for placing them in the closed position thereof.

Another object of the invention proposes providing the under side of one of the beads with a first small projection against which an extended tail of the first clip is adapted to engage in a manner to be stopped while the remaining clips are formed with the shorter tail in a manner to pass this first small projection.

Another object of the invention proposes forming a series of progressively increasing in size small aligned projections on the top side to the other of said beads for stopping sliding of the metal clips with these clips being provided with progressively increasing in size grooved portions arranged in a manner to permit the endmost clips of the middle set of clips to pass the first projections.

Another object of this invention proposes the formation of a last small projection on the second bead off the line of the series of aligned projections in a manner to stop the last clip in its proper position after each of the other clips have been stopped in their proper position by their respective projections.

Still another object of the invention proposes forming each of the clips from a single strip of metallic material bent into the desired shape with each being formed with a grip portion for engaging one of the beads to frictionally maintain the clips in position upon the beads and spaced finger portions arranged in a manner to be manually gripped to be moved into desired positions upon the beads.

A further object of this invention is to construct a slide fastener which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

2

Fig. 1 is a side elevational view of a cosmetic purse provided with a slide fastener constructed in accordance with this invention.

Fig. 2 is a plan view of Fig. 1 with the clips moved to their open position.

Fig. 3 is an enlarged vertical sectional view taken on the line 3—3 of Fig. 1.

Fig. 4 is an enlarged partial horizontal sectional view taken on the line 4—4 of Fig. 1.

10 Fig. 5 is a view similar to Fig. 1, but illustrating a modification of the invention.

Fig. 6 is an enlarged horizontal sectional view taken on the line 6—6 of Fig. 5.

Fig. 7 is an enlarged vertical sectional view taken on the line 7—7 of Fig. 5.

15 Fig. 8 is an enlarged vertical sectional view taken on the line 8—8 of Fig. 5.

The slide fastener, according to this invention, is arranged in the nature of a closure for an article 10. The article 10 on the drawings is in the

20 form of a cosmetic bag having adjacent flexible beads 11 and 12 extending along the open top edges of the article with a series of clips 13^a and 13^b slidably mounted on the beads for location at different distances from one end of the article 10 for closing the same. The beads 11 and 12 are formed by encasing cords 30 within hems 31 formed along the top edges of said cosmetic bag. These clips 13^a, 13^b are each formed by a single strip of metal bent in a manner to engage

25 about the beads 11 and 12 and arranged to retain beads 11 and 12 immediately adjacent one another to keep the article 10 closed. However the clips 13^a, 13^b may be collected at one end of

30 the open top of article 10 as shown in Fig. 2 permitting the beads 11 and 12 to be expanded to the position illustrated by the dot and dash lines 11' and 12' in Fig. 2 for opening the top of the article 10, permitting the contents to be removed therefrom.

35 The cord 12 is preferably smaller in diameter than the cord 11 to leave space for the fabric of article 10 to pass thereover.

40 A first small projection 14 is formed on the under side of the bead 12 for stopping sliding of the clip 13^a. The projection 14 is merely a lump of thread embroidered or knotted on the material adjacent the bead 12. The bead 11 is provided on one side with a projection 15 for stopping sliding of the clip 13^b. The projection 15 is merely a lump of thread embroidered or knotted

45 on the bead 11.

The clip 13^a is formed with a long tail end 16 which is arranged to strike the small projection 14 (see Fig. 4) and the clip 13^b is formed with a short tail 17 adapted to pass the small projection 14 and permit the clip 13^b to be slid to a position beyond the small projection 14. The clip 13^b is arranged to be slid past the small projection 14 until it strikes the projection 15 on

50 the side of the bead 11 as shown in Fig. 1.

55 It will be noted that the location of the projections 14 and 15 will act to evenly space the

clips 13^a and 13^b along the length of the beads 11 and 12 in a manner to retain the beads in a position in which they close the top of the article 10. However they are capable of being collected at one end of the beads 11 and 12 and more specifically the right hand end of Fig. 2 in a manner to free the beads 11 and 12 to be expanded as previously described.

Each of the clips 13^a, 13^b is formed with a grip portion 18 in the form of a portion of the material of the clip bent to bear against one of the beads in a manner to frictionally grip the same and retain the clips against accidentally sliding along the length of the beads 11 and 12. Each of the clips is further provided with outwardly extended finger portions 19 designed to provide a grip for the fingers of the hand used in moving the clips along the length of the beads 11 and 12.

In the form of the invention shown in Figs. 5 to 8, the construction of the slide fastener is similar to that previously described except for the provision of a greater number of clips for closing the article 20. This article 20 is in the form of a bag having adjacent beads 21 and 22 arranged along the open top edges thereof with a series of clips 23 provided for location at different distances along the length of the beads 21 and 22 in a manner to close the open top thereof.

The material adjacent the bead 22 is provided at its under side with a small projection 24. This projection 24 is designed to restrain sliding of the first clip 23^a. This first clip 23^a is formed with a long tail 25 which is adapted to strike the projection 24. Each of the other clips 23^b is formed with a short tail 26 which is adapted to pass the projection 24 and permit these clips to be slid to a position beyond 24.

Projections 27 and 28 are formed on the top side of the material adjacent the bead 21 for stopping sliding of the second clip 23^b and the third clip 23^c the projection 28 being larger than the projection 27.

A last small projection 29 is formed upon the side of the material adjacent the bead 21 out of line with the series of aligned projections 27 and 28 (see Fig. 5) for stopping sliding of the last clip 23^d. The projection 29 is merely a lump of thread embroidered or knotted on the bead 21.

The last of the clips 23^d is formed with a grooved portion 31 of a size to pass over the series of aligned projections 27 and 28 to permit this last clip 23^d to reach a position and strike the last small projection 29 to be stopped thereby.

The clips 23^c and 23^d have grooved portions 31 progressively increasing in size comparative with the progressively increasing projections 27 and 28 for stopping sliding of the clips at different positions.

Each of the clips 23 is formed with a grip portion 32 for gripping one of the beads to maintain the clips 23 frictionally in position along the length of the beads 21 and 22. Each of the clips is further provided with spaced finger portions 33 adapted to be manually gripped by the fingers of the hand moving the clips to desired positions along the length of the beads 21 and 22.

In the two forms of the invention shown on the drawings all of the projections used for stopping the clips at desired positions are formed by embroidering a bulge of thread at desired positions upon the beads.

While I have illustrated and described the preferred embodiments of my invention, it is to be

understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a closure for an article having an opening with flexible beads extending along the edges thereof and a series of clips slidably mounted on said beads for location at different distances from one end of said article, means for stopping said clips at spaced positions along the length of said beads, comprising a first small projection on the material adjacent one of said beads for stopping sliding of the first one of said clips, a series of progressively increasing in size small aligned projections on the material adjacent the other of said beads for stopping sliding of the remainder of said clips, a last small projection on said second named bead off of the line of said series of aligned projections for stopping the last one of said clips, the first one of said clips having a long tail end for striking said first small projection and the other clips having short tails for passing said first small projection, the last of said clips having a grooved portion for passing over said series of aligned projections for reaching and striking said last small projection, the clips between said first and last clips having grooved portions of progressively increasing sizes cooperative with said progressively increasing projections for stopping sliding of said clips at predetermined different positions.

2. In a closure for an article having an opening with flexible beads extending along the edges thereof and a series of clips slidably mounted on said beads for location at different distances from one end of said article, means for stopping said clips at spaced positions along the length of said beads, comprising a first small projection on the material adjacent one of said beads for stopping sliding of the first one of said clips, a series of progressively increasing in size small aligned projections on the material adjacent the other of said beads for stopping sliding of the remainder of said clips, a last small projection on said second named bead off of the line of said series of aligned projections for stopping the last one of said clips, the first one of said clips having a long tail end for striking said first small projection and the other clips having short tails for passing said first small projection, the last of said clips having a grooved portion for passing over said series of aligned projections for reaching and striking said last small projection, the clips between said first and last clips having grooved portions of progressively increasing sizes cooperative with said progressively increasing projections for stopping sliding of said clips at predetermined different positions.

ISIDORE GOLDSTEIN.
